UNITED STATES PATENT OFFICE.

JOHN ROBERT KELLEY, OF COVINGTON, KENTUCKY.

RADIOGRAPHIC APPARATUS.

Application filed May 17, 1926. Serial No. 109,610.

My invention relates to improvements in radiographic apparatus. One of its objects is to provide improved apparatus whereby the X-ray generating member or tube may be adjusted during the interval between two photographic exposures without liability to set up vibrations in the apparatus, which vibrations would be liable to affect the quality and accuracy of the negatives and positives resulting from such exposures made while the apparatus was vibrating. Another object is to provide improved radiographic apparatus adapted to take stereo-radiographs by shifting the position of the X-ray generator during the interval between two closely following photographic exposures without liability to set up vibration in the supporting apparatus due to shifting the position of the X-ray generating apparatus. Another object is to provide improved apparatus adapted to permit relatively quick adjustment of X-ray generators during the interval between two photographic exposures without developing vibration in the apparatus, and which is not materially altered or affected by the amount of or by changes in the weight of the X-ray generators. My invention also comprises certain details of form and arrangement, and combination of components, all of which will be fully set forth in the description of the accompanying drawings, in which:—

Fig. 1 is a plan of a radiographic apparatus embodying my invention.

Fig. 2 is a front elevation of the apparatus of Fig. 1.

Fig. 3 is a view similar to Fig. 2 of part of the apparatus thereof in a different position of adjustment.

Fig. 4 is a side elevation of the apparatus of Fig. 3.

Fig. 5 is a sectional detail through one of the actuating electrical solenoids.

Fig. 6 is a detail of one of the plate holder latches and latch releasing structures.

Fig. 7 is a wiring diagram illustrating one means of releasing and shifting the photographic plates and the X-ray generating member.

Fig. 8 is a detail of the plate holder frame and plate holders.

The accompanying drawings illustrate the preferred embodiment of my invention in which 15 represents a stationary frame upon which is mounted a photographic plate holder carriage 16, which is guided vertically by

the vertical tubular guides 17 of the frame 15, and which is counterbalanced so as to move readily and freely from one position to another by means of counterweights 60 located and movable vertically within the tubes 17. At the upper ends of the tubes 17 are stationary plates 18 upon which are mounted and journaled sprocket wheels 19 over which are drawn sprocket chains 20. 65 These chains are connected at one end to the plate holder carriage, and at their opposite ends to the counterweights located within the tube 17. The exterior of the tubes 17 are preferably provided with racks 21 and 70 22 which are engaged by pinions 23 upon a shaft 24 journaled to the carriage 16 and actuated by hand wheels 25 at either end thereof to raise or lower the carriage 16. The carriage 16 may be pushed by hand up or 75 down to any desired position, which it will retain until moved to another position. A shaft 26 journaled to the carriage 16 is provided with and adapted to actuate and release clamping jaws, which clamp the carriage rigidly upon the tubes 17 to any desired position of adjustment.

A plate holder carrying frame 27 is pendulously supported within the frame or housing of the carriage 16 by means of links 85 28 and 29 which are pivotally attached at their upper ends to the carriage 16 at 74 and 75 and at their lower ends are pivotally attached to the plate holder carrying frame 27 at 76 and 77. The frame of the carriage 16 90 comprises two sections 30 and 31 which are impervious to light rays and impervious to X-rays, and a central section 32 which is pervious to X-rays but impervious to light rays. The frame 27 is adapted to support 95 two or more photographic plate holders 78 and 79 side by side so as to expose one of said plate holders in rear of the section 32 of the carriage 16, with the other plate holder in position in rear of one or other of the 100 sections 30 and 31. By a pendulous movement of the plate holder frame 27, the opposite plate holder is adapted to be shifted to position in rear of the carriage section 32, and the plate holder originally in rear 105 of the carriage section 32 shifted to a position in rear of one of the carriage sections 30 or 31.

The plate holder carrying frame 27 is provided with flexible fingers 34 and 35 at 110 opposite ends thereof attached preferably to the lower ends of the links 28 and 29. These

flexible fingers are designed to each enter between a rigid jaw 36 and a pivotally mounted jaw 37, see Fig. 6, so as to automatically latch the frame 27 to the carriage 16 at exactly the extremity of its pendulous movements in order to avoid imparting vibration to the frame 27 or carriage 16 due to such pendulous movement of the frame 27. The finger 34 or 35 enters freely between the jaws 36 and 37, lifting the spring actuated jaw away from the rigid jaw against the action of its spring 38, until the finger has reached its maximum movement and comes to a position of rest whereupon the spring actuated jaw 37 grips the flexible finger rigidly against the face of the rigid jaw 36 before the frame 27 has had a chance to commence its retrograde movement, or to acquire velocity of momentum on a retrograde movement, and hence without developing vibration either in frame 27 or carriage 16.

A solenoid 39 is adapted when electrically energized to actuate an electro-magnetic armature and cause the end 40 of said armature to engage the upper end of the jaw 37 counteracting the spring 38 and releasing the grip of the jaw 37 upon the flexible finger 34 or 35 to thereby release the frame 27 and permit said frame 27 to make another pendulous movement but in the opposite direction where its opposite finger 34 or 35 is gripped by the opposite pair of jaws 36 and 37. During the interval between two pendulous movements of the frame 27, sufficient static energy is applied or imparted to the frame 27 either automatically or manually to compensate for the energy lost through friction and similar resistance to movement, and to thereby cause the several pendulous movements of the frame 27 to be of substantially equal length, as for instance by manually shifting the weight 80, see Fig. 2, from one to the other side of the center 75.

The patient or object to be radiographed is adapted to stand in front of the previous section 32 of the carriage 16, which is vertically adjustable to positions opposite any portion of the body of the patient when standing, or if desired, the patient may be supported upon a hospital cot 42, which is adapted to be wheeled into position between the columns 17 with the patient thereon, and the carriage adjusted to position and the patient lifted to a sitting position in front of the carriage section 32, as indicated in dotted lines in Figs. 1 and 2.

In order to make a radiographic exposure the X-ray generator or tube 44 is detachably mounted between the forked ends of a crossbar 45 which is pivotally mounted at 46 upon and relative to a carriage 48 vertically adjustable upon a vertical standard 47 which is preferably rigidly mounted and at-

tached at top and bottom relative to the frame 15 and tubes 17. The carriage 48 is preferably counterbalanced upon the standard 47 by means of a sprocket chain 49 attached at one end to the carriage 48, and leading from thence over the idler pulley 50 at the upper end of the standard 47, and over a sprocket wheel 51 rigidly mounted relative to one of the sprocket wheels 19 so as to rotate in unison therewith, and thence to a weight 52. The carriage 48 is thus automatically adjusted up and down upon the standard 47 in unison with the movements of the carriage 16 upon the columns 17, and clamping of the carriage 16 in position serves also to prevent displacement of the carriage 48.

For the taking of stereographic radiographs it is desirable for the X-ray generator 44 and arm 47 to move from one position to another position during the interval that the plate holder frame 27 is making one of its pendulous movements to carry the first or exposed photographic plate away from the rear of section 32 of carriage 16 and in rear of a section 30 or 31 thereof, and at the same time bringing a second or unexposed plate in position in rear of the carriage section 32. This movement of the X-ray generator 44 and arm 47 should take place in a relatively short interval of time, in order that the position of the object shall not change, and it is important that such movement of the generator 44 and arm 47 shall not develop or set up vibration in the X-ray generator or any of the plate or generator supporting members. The fact that X-ray generators are frequently changed, and that they vary greatly in weight further complicates the problem of a movement of the generator without developing vibration. A counterweight 70 adjustable upon the end of arm 45 provides for adjustably counterbalancing different X-ray generators of variable weight.

In order to shift the X-ray generator during the interval between the exposure of two sensitive plates and irrespective of any change in the weight of the X-ray generator, without developing vibration, I provide an arm 53 depending from the cross bar 45, and provided with a weight or pendulum 54 preferably adjustable vertically upon the arm 53 by means of nuts 55 and 56 above and below said pendulum. The pendulum 54 causes the crossbar 45 and X-ray generator to tend to sway to and fro within prescribed time limits, and at opposite limits of its pendulous movement to come to a position of rest before commencing a movement in the opposite direction. In order to lock the crossbar 45 and X-ray generator 44 after they have come to a position of rest and before they have commenced a movement in the opposite direction, I pro-

vide a yoke 58 attached rigidly to the crossbar 45. Between the arms of the yoke 58 is an eccentric wheel 59, which is journaled eccentrically upon a stud shaft 60 relative to the carriage 48. Also mounted rigidly relative to the eccentric wheel 59 and pivotally upon the stud shaft 60 is a cam-plate 61 having inclined cam faces 62 and 63 adapted alternately to move into operative relation with the end 64 of an electro-magnetic armature housed within the electromagnetic coil 65, and adapted to be actuated thereby.

In the position shown in Fig. 2, the periphery of the eccentric wheel is in engagement at opposite edges with the inner faces of the yoke 58 with practically no lost motion, and the eccentric wheel is upon dead center with reference to any tendency of the crossbar 45, yoke 58 or X-ray generator 44 to move upon their axis 46, thereby locking the crossbar 45, X-ray generator 44, and pendulum 54 at one limit of their pendulous movements, and against their natural tendency to move toward a position of equilibrium. The cam face 62 is at the same time in position to be engaged by a thrust of the end of the armature 64 to cause the cam plate 61 and eccentric wheel 59 to make one half of a rotation or to reach the position shown in Fig. 3. The thrust of the end of the armature 64 furnishes sufficient energy in addition to that supplied by the pendulum to cause the crossbar 45 and pendulum to swing through substantially the same arc of a circle at each operation of the armature 64 and to shift the position of the X-ray generator 44 without imparting vibration to any portion of the apparatus. If desired the armature 64 may be manually operated by striking the rear end 68 of the armature lightly by hand. The structure of the armatures 64 and 40 and coils 65 and 39 are substantially the same and are each shown in detail in Fig. 5. The coils 39 at opposite ends of the plate holder carriage 16 and the coil 65 are adapted to be connected up in a variety of parallel or independent electrical circuits to be actuated by the operator as may be desired. In Fig. 7 I have shown diagrammatically one type of electrical circuit adapted to be so employed, and in which the two coils 39 and the coil 65 are included.

The apparatus herein shown and described is capable of considerable modification within the scope of the claims without departing from the spirit of my invention.

What I claim is:

1. A radiographic apparatus comprising sensitive plates to be radiographically exposed, an X-ray generator, a pivotally mounted support for said generator having a pendulous movement to adjust the position of said generator, and means operable to

positively lock said support and generator alternately at opposite extremities of the pendulous movement of said support to thereby adjust said X-ray generator from one position to another position without exciting vibratory movement in said generator or its supporting members. 70

2. A radiographic apparatus comprising sensitive plates to be radiographically exposed, a radiographic generator, a pendulously movable supporting member adapted to support and adjust said generator from one position to another, a locking member operable to positively lock said supporting member and generator at opposite extremities of the pendulous movement of said supporting member to thereby adjust said generator from one position to another position without exciting vibratory movement in said generator or its supporting member. 80

3. A radiographic apparatus comprising adjustably mounted sensitive plates to be radiographically exposed, a radiographic generator adapted to be adjusted during the time interval between the exposure of one plate and the exposure of another plate from one position to another position, a pendulously movable generator supporting member adapted to support and adjust said generator from one position to another, a locking member, operative to positively lock said supporting member and generator at opposite extremities of the pendulous movement of said supporting member to thereby adjust said generator from one position to another position without exciting vibratory movement in said generator or its supporting member. 90

4. A radiographic apparatus comprising sensitive plates to be radiographically exposed, a radiographic generator, a pendulously movable supporting member adapted to support and adjust said generator from one position to another position, a locking member movable from one position to another position and operable to positively release said supporting member from a locked position at one end of its pendulous movements and to lock it to another position at the opposite extremity of its pendulous movements to thereby adjust said generator from one position to another position, without exciting vibratory movement in said generator or its supporting member. 110

5. A radiographic apparatus comprising sensitive plates to be successively radiographically exposed, a radiographic generator pendulously supported and movable cyclicly from one position to another position during the interval between one radiographic exposure and another radiographic exposure, and a locking member movable from one position to another position and operable to release said generator from a locked position at one extremity of its pen- 120

dulous movements and to lock it to another position at the opposite extremity of its pendulous movements, to thereby adjust said generator from one position to another position without exciting vibratory movement in said generator.

6. A radiographic apparatus comprising sensitive plates to be successively radiographically exposed, a radiographic generator, a pendulously movable supporting member adapted to support and adjust said generator from one position to another position, a freely movable reciprocatory eccentric adapted to engage said supporting member and to lock said supporting member and generator at opposite extremities of said pendulous movement to thereby release said supporting member and generator from one position and lock them to another position without exciting vibratory movement in said generator or its support.

7. A radiographic apparatus comprising sensitive plates to be successively radiographically exposed, a radiographic generator, a pendulously movable supporting member adapted to support and adjust said generator from one position to another position, a freely movable reciprocatory eccentric adapted to engage said supporting member and to lock said supporting member and generator at opposite extremities of said pendulous movement to thereby release said supporting member and generator from one position and lock them to another position without exciting vibratory movement in said generator or its support, an eccentric actuating member having a limited movement, and electrically energized mechanism to engage said actuating member to thereby shift said eccentric from one position to another position.

8. A radiographic apparatus comprising a plate holder carriage and a radiographic generator carriage both vertically adjustable and counterbalanced and connected to move

vertically in unison, a plurality of sensitive plates pendulously supported upon said plate holder carriage and adapted to be successively radiographically exposed, a radiographic generator pendulously supported relative to said generator carriage and movable cyclicly from one position to another position during the interval between one radiographic exposure and another radiographic exposure, and a locking member movable from one position to another position and operable to release said generator from a locked position at one extremity of its pendulous movements and to lock it to another position at the opposite extremity of its pendulous movement, to thereby adjust said generator from one position to another position without exciting vibratory movement in said generator.

9. A radiographic apparatus comprising a plate holder carriage and a radiographic generator carriage both vertically adjustable and counterbalanced and connected to move vertically in unison, a plurality of sensitive plates pendulously supported upon said plate holder carriage and adapted to be successively radiographically exposed, a radiographic generator pendulously supported relative to said generator carriage and movable cyclicly from one position to another position during the interval between one radiographic exposure and another radiographic exposure, a locking member movable from one position to another position and serving to release said generator from a locked position at one extremity of its pendulous movement and to lock it to another position at the opposite extremity of its pendulous movement, and means controllable by the operator to shift said generator locking member from one position to another position.

In testimony whereof I have affixed my signature.

JOHN ROBERT KELLEY.
